UNITED STATES PATENT OFFICE.

WILLIAM C. NORCROSS, OF TERRE HAUTE, INDIANA, ASSIGNR TO NORCROSS MOULDING MACHINE COMPANY, OF TERRE HAUTE, INDIANA, A CORPORATION OF INDIANA.

SAND-MOLDING MACHINE.

No. 873,584.

Specification of Letters Patent.

Patented Dec. 10, 1907.

Application filed December 6, 1905. Serial No. 290,543.

To all whom it may concern:

Be it known that I, WILLIAM C. NORCROSS, a citizen of the United States, residing at Terre Haute, in the county of Vigo and State of Indiana, have invented new and useful Improvements in Sand-Molding Machines, of which the following is a specification.

This invention relates to sand molding machines, and its object is to effect a rapid and thorough packing of the sand around the pattern by jarring the support on which the flask rests. I am aware that it has been proposed by others to accomplish this result by various kinds of mechanism, but my invention consists in certain new and simple devices for performing the work, as hereinafter set forth and particularly pointed out in the claims.

20 The accompanying drawing is an elevation, half in section, of my improved molding machine.

On a suitable heavy metal base-plate 1 is secured the upright cylinder 2, in which is fitted the trunk piston 3 provided at its lower end with a projection, such as a plug 4 preferably of steel, which strikes the base-plate when the piston is at the bottom of its stroke. A pipe 5 enters the lower end of the cylinder and is provided with a stop valve 6. A few inches above the bottom of the cylinder is a plurality of ports 7 connecting the cylinder with an annular chamber 8 surrounding the cylinder. An exhaust pipe 9 leads from this chamber and is provided with a stop valve 10. When the plug 4 rests on the base-plate, the ports 7 are covered by the piston, whose bottom stands a little below said ports, as shown in the drawing. Near the upper end of the cylinder is a safety relief port 11.

The table 12 is supported by the piston, being preferably attached thereto by a central boss 13 which enters the upper end of the piston. Resting on the table is a plate 14 to which the pattern 15 is fastened. Surrounding the pattern is a stripping plate 16, lying loosely on the plate 14, and standing on the stripping plate is the flask 17. A false flask, ring or box 18 is preferably placed on top of the flask 17 to hold loose sand enough to supply what may be wanted after that in the flask proper has been settled down about the pattern.

55 At two or more points around the cylinder

are located standards 19 rising above the position occupied by the flask when the sand is being packed. On each standard is a collar 20, adjustable vertically thereon and provided with a set screw 21 for clamping it at any desired height. Resting on each collar and rotatable freely on the standard is a catch 22, consisting preferably of a plate having a projection 23 on one side.

The operation of the machine is as follows:—The pattern is fastened to the plate 14 and the plate is placed on the table 12. The stripping plate 16 is then dropped into position, and the flask and ring are placed thereon around the pattern and filled with sand in any convenient way. The valves 6 and 10 are then opened, admitting fluid pressure through the pipe 5 into the space below the piston, which at once rises until the ports 7 are uncovered. The sudden escape of pressure through these ports lets the piston drop, and the striking of the plug 4 on the base-plate jars the sand down into and around the pattern. The fall of the piston closes the exhaust ports and permits the fluid pressure from the supply pipe to accumulate and lift the piston again. This operation is repeated very rapidly, the strokes approximating three hundred per minute. Less than one minute is required to ram the mold, the exact time varying according to the pattern and the flask. After the mold has been rammed sufficiently, both valves are closed, the ring 18 is removed, and the surplus sand is struck off. The supply valve 9 is then re-opened, and the piston and its load are raised by a long stroke of the piston to a height sufficient to permit the catches to be turned around under the edges of the stripping plate. The port 11 prevents the piston from rising too high by relieving the pressure before the piston has been blown out of the cylinder. The valve 10 is then opened, and the piston drops, carrying with it the pattern and leaving the mold supported on the stripping plate. The completed mold having been removed, another flask is then placed on the stripping plate, the piston is raised to pick them up, the catches are turned back, and the new flask is lowered to receive the ring and be filled with sand. The ramming operation is then repeated.

It will be noted that after the valves are opened, the reciprocation of the piston is automatic, the piston itself serving as the

valve to open and close the exhaust ports. The combined area of these ports is greater than that of the supply pipe, so that the sudden reduction of pressure under the piston will be so great that the supply pipe will not be able to make it up immediately, and thus the piston can drop far enough to produce the jar before the pressure becomes sufficient to lift the piston again. By regulating the valves the travel of the piston can be varied so that it will give either a hard blow or a light one, or even dance in the air without striking the base-plate, if desired.

The subject-matter of this application has been previously disclosed in my application Serial Number 200,550, filed March 29, 1904.

Having thus described my invention, what I claim is:

1. In a sand molding machine, means for jarring the mold, comprising an upright cylinder having normally-open fluid pressure supply pipe and exhaust ports, and a piston controlling said ports in its up and down strokes, and arranged to strike the bottom of the cylinder on its down stroke.
2. In a sand molding machine, means for jarring the mold, comprising an upright cylinder having a normally-open fluid pressure supply pipe at its bottom and a plurality of exhaust ports in its walls, the area of said ports being considerably greater than that of the supply pipe, and a piston controlling said exhaust ports and supported normally by the bottom of the cylinder.
3. In a sand molding machine, means for jarring the mold, comprising an upright cylinder having a fluid pressure supply pipe entering it at its bottom, a plurality of exhaust ports in its walls, an annular chamber into which said ports open, an exhaust pipe leading from said chamber, stop valves in the supply pipe and exhaust pipe, and a piston in the cylinder controlling said exhaust ports.
4. In a sand molding machine, the combination

with an upright cylinder having a supply port in its lower end and exhaust ports at a point above the supply, of a piston fitting in said cylinder and supported normally by the bottom of the cylinder at a point below said exhaust ports and serving to open said exhaust ports when it rises past them, and a pattern-supporting table carried on the upper end of said piston.

5. In a sand molding machine, the combination with suitable catches, of a table for supporting the pattern and the flask, an upright cylinder, a piston therein on which said table rests, and means for giving said piston rapid short strokes striking the end of the cylinder to pack the sand, a long up-stroke to raise the flask to a position to engage with the catches, and a long down-stroke to withdraw the pattern from the mold.

6. In a sand molding machine, the combination with a table for supporting the pattern and the flask, of an upright cylinder containing a plurality of exhaust ports, a piston carrying said table and reciprocating in said cylinder above and below said exhaust ports and striking the bottom of the cylinder at every stroke, a pipe conveying fluid pressure to said cylinder below said piston, and a regulating valve in said pipe.

7. In a sand molding machine, the combination with an upright cylinder, having a constantly-open supply port in its lower end and exhaust ports at a suitable distance above the supply port, of a piston in said cylinder controlling said exhaust ports, and a projection on the bottom of said piston adapted to strike the bottom of the cylinder.

In testimony whereof I have signed my name to this specification in the presence of two subscribing witnesses.

WILLIAM C. NORCROSS.
